Primary Examiner — Katrina A Betton(74) *Attorney, Agent, or Firm* — Kyle R. Satterthwaite; Ryan W. Dupuis; Ade & Company Inc.(57) **CLAIM**

The ornamental design for a stabilization support for a recreational vehicle, as shown and described.

DESCRIPTION

FIG. 1 is a perspective view showing my new design;

FIG. 2 is a top plan view showing my new design;

FIG. 3 is a right side elevational view showing my new design;

FIG. 4 is a left side elevational view showing my new design;

FIG. 5 is a bottom plan view showing my new design;

FIG. 6 is a front elevational view showing my new design;

FIG. 7 is a rear elevational view showing my new design; and,

FIG. 8 is a perspective view of the stabilization support during use with a second matching stabilization support, a ratchet strap and a recreational vehicle, each of which is shown in broken lines and forms no part of the claimed design.

Portions of the stabilization support shown in broken lines form no part of the claimed design.
